UNITED STATES PATENT OFFICE.

LOUIS K. GILLSON, OF WILMETTE, ILLINOIS.

FUEL-THROWING VANE OR SHOVEL.

Application filed March 4, 1926. Serial No. 92,137.

The invention relates to vanes or shovels adapted to be mounted for oscillation to project fuel into a fire-box, of the type disclosed in the patent issued to Albert G. 5 Elvin, No. 1,058,356, April 8, 1913.

Devices of this character have two somewhat different functions to perform. They must scatter, broadcast, the major part of the fuel which they project over a wide ex- 10 panse of the grate area, and must deposit a sufficient amount of fuel in the rearward portion of the fire-box.

The object of the present invention is to provide for the performance of each of these 15 functions without interference with the performance of the other.

While the invention may be structurally embodied in forms differing somewhat in detail, preferred forms of construction are 20 hereinafter described and are illustrated in the accompanying drawings, in which—

Fig. 1 is a plan view of the improved vane or shovel;

Fig. 2 is a front elevation thereof;

Fig. 3 is a front elevation of the device, showing a modified form of construction; and

Fig. 4 is a bottom plan view of the device shown in Fig. 3.

The improved vane or shovel comprises a blade 10, which when in service position is approximately vertical. This vane may be substantially straight or may be given such form as may best adapt it for use in the fire- 30 box with which it is to be associated, the configuration of the blade being varied as may be found advisable in practice accord- 35 ing to the length and width of the fire-box.

This blade is provided adjacent one end 40 with a hub 11 provided with an eye, the axis of which is substantially parallel with the face of the blade and is adapted to fit upon and be firmly bound to a shaft from which it is given movement. In order to prevent 45 all the fuel from being thrown forwardly by the centrifugal action of the swinging vanes, said vanes are provided with one or more walls extending outwardly at an angle to the plane of said vanes to form one or more 50 compartments or pockets for retaining a portion of the fuel during the accelerating period of the vane movement and to deliver it over the rear portions of the firebox during the final movement of the vane. These

compartments or pockets open forwardly, 55 are without bottom walls.

In the form of the device shown in Figs. 1 and 2, which is by way of example only, a shelf 12 projects forwardly from the blade 10, somewhat above its lower margin, and a 60 plurality of flanges or walls 13 depend from the shelf 12 and are arranged transversely thereof, these flanges extending downwardly approximately to the lower margin of the 65 blade 10.

An increment of fuel having been deposited in front of the vane or shovel when the latter is in its retracted position, is swept forwardly by its advance movement. So much of the fuel as lies above the level of 70 the shelf 12 is scooped up by it, and as the vane or shovel moves forwardly at high speed it slides along on the shelf and against the face of the blade, and is delivered therefrom by centrifugal action and is broad- 75 casted over the forward portions of the grate area, little or none of it, however, reaching the rearward portion of the grate or back corners of the fire-box. So much of the fuel as lies below the level of the shelf 12 is gathered in the pockets thereunder formed by the flanges 13 and is held by them against projection by centrifugal force. 80

In the use of fuel projecting devices of this character in connection with mechanical 85 stokers, it is the practice to decelerate the forward movement of the vane or shovel as it approaches the end of its forward stroke. At this period of the stroke the vane or 90 shovel is substantially parallel with the longitudinal axis of the fire-box, and when the stroke ends it will have passed beyond this parallel. The fuel contained in the pockets will be discharged therefrom by its momentum and scattered along the rearward portion of the grate and into the back corner of 95 the fire-box. It is customary to use two of these projectors, as shown in the Elvin patent referred to, one of them serving the left side and the other the right side of the grate. 100

There is an advantage in subdividing the space below the shelf into a plurality of pockets, in that the fuel retained for delivery to the rearward portion of the fire-box is thus separated into a number of small increments and objectionable impacting of the mass against the transverse flanges is avoided. The number of pockets, as well as

the height of the shelf, will be determined by the character of the fuel, particularly as to size, by the velocity imparted to the projector on its forward stroke, and by the size and shape of the fire-box.

In the construction illustrated in Figs. 1 and 2, four of the flanges 13 are shown, and consequently four separate pockets are provided. The number may be varied as well 10 as their location with reference to the length of the blade.

In the construction illustrated in Figs. 3 and 4, there are but two pockets shown, and instead of the uniformly straight shelf 12 15 there is employed a shelf 14, which extends backwardly from the end of the vane approximately to one-half its length and is then inclined downwardly to its lower margin, and the forward edge of the downwardly inclined portion may be inclined backwardly toward the blade, as plainly shown 20 in Fig. 4. In these figures the upstanding or body portion 15 of the vane is shown as straight. All of the fuel which may be encountered by that portion of the blade which 25 is nearer the hub than the lowest portion of the shelf will be carried up this incline by centrifugal force and thrown forwardly into the fire-box.

30 A further advantage of the improved vane or shovel is that a minimum frictional retardation of the fuel intended to be scattered forwardly is secured. Should the fuel be retained by transverse ribs or flanges not 35 surmounted by a shelf, all of that portion of the fuel which is to be thrown forward would be retarded by its frictional engagement with the lower portion which is retained for delivery into the back portion 40 of the fire-box.

In the appended claims the device is defined and described as in service position.

I claim as my invention—

45 1. A fuel projecting vane or shovel adapted to be mounted for oscillation in a horizontal path and comprising an upstanding blade, a shelf projecting forwardly from the blade and above the bottom margin thereof, and a transverse flange depending from 50 the shelf.

55 2. A fuel projecting vane or shovel adapted to be mounted for oscillation in a horizontal path and comprising an upstanding blade, a shelf projecting forwardly from the blade and above the bottom margin thereof,

and a plurality of transverse flanges depending from the shelf.

3. A fuel projecting vane or shovel adapted to be mounted for oscillation in a horizontal path and comprising an upstanding 60 blade, a shelf projecting forwardly from the blade and above the bottom margin thereof and being downwardly inclined toward the heel of the blade, and a transverse flange depending from the shelf.

4. A fuel projecting vane or shovel adapted to be mounted for oscillation in a horizontal path and comprising a substantially straight upstanding blade, a shelf projecting forwardly from the blade and above the bottom margin thereof, and a transverse flange 70 depending from the shelf.

5. A fuel projecting vane or shovel adapted to be mounted for oscillation in a horizontal path and comprising an upstanding 75 blade, and a plurality of walls extending outwardly from the plane of said vane to form compartments open at their front and lower sides.

6. A fuel projecting vane or shovel adapted to be mounted for oscillation in a horizontal path and comprising an upstanding blade, and a web projecting horizontally from the face of the blade for separating 80 portions of the area thereof.

85 7. A fuel projecting vane or shovel adapted to be mounted for oscillation in a horizontal path and comprising an upstanding blade, and a web projecting vertically from the face of the blade for separating portions 90 of the area thereof, said web and blade forming a pocket open at its front and bottom sides.

8. A fuel projecting vane adapted to be mounted for oscillation in a horizontal path 95 and comprising an upstanding blade, the upper portion of the face of which is horizontally unobstructed, its lower portion being configured to provide a forwardly open and upwardly covered fuel receiving pocket.

100 9. A fuel projecting vane adapted to be mounted for oscillation in a horizontal path and comprising an upstanding blade, the upper portion of the face of which is horizontally unobstructed, its lower portion being 105 configured to provide a plurality of forwardly open and upwardly covered fuel receiving pockets.

In testimony whereof I affix my signature.
LOUIS K. GILLSON.
